UNITED STATES PATENT OFFICE.

JOSEPH HORVATH, OF DETROIT, MICHIGAN.

LUBRICATOR.

1,291,000.

Specification of Letters Patent.

Patented Jan. 14, 1919.

Application filed October 2, 1917, Serial No. 194,336. Renewed September 27, 1918. Serial No. 255,992.

To all whom it may concern:

Be it known that I, JOSEPH HORVATH, a subject of the Emperor of Austria, and residing at Detroit, in the county of Wayne 5 and State of Michigan, have invented a new and Improved Lubricator, of which the following is a specification.

This invention relates to automatic lubricators of the same general type as those 10 shown in my pending application, Serial Number 154,093, and to self-closing filling devices for such lubricators and other containers requiring filling devices that may be firmly held in closed position.

15 This invention consists in the details of construction illustrated in the accompanying drawing and particularly pointed out in the claims.

In the drawings, Figures 1 and 2 are central longitudinal sections of one embodiment 20 of the present invention showing the filling device in two positions. Figs. 3 and 4 are similar sections of another embodiment of the invention and Fig. 5 is an elevation 25 thereof. Fig. 6 is a section of the filling device and plan of the guide plate of the structure shown in Fig. 3. Fig. 7 is a section of the filling plunger and plan of the upper part of the body shown in Fig. 2.

30 Similar reference characters refer to like parts throughout the several views.

The lubricant receptacle, the cap therefor, the guide plate therein, the movable plunger and the cap or button at the upper end 35 of the plunger are all preferably stamped out of sheet metal, brass or steel being the metals usually employed. In Fig. 1, the lubricant receptacle or body 1 of the lubricator is formed with a threaded neck 2 by means 40 of which it is attached to the part to be lubricated and in which neck a short discharge tube 3 is securely held. The cap 4 may be formed with a proper inwardly extending guide and sealing flange 5 provided with a 45 notch 6 to permit the rib or spline 7 on the plunger 8 to slide freely therein.

The guide plate 9 has a circumferential cylindrical flange 10, and a spring 12 between this guide plate and the flange 13 at 50 the lower end of the plunger 8 normally holds the plunger down. A cap or button 14 is secured to the upper end of the plunger and receives a washer 15 that serves as a packing to prevent leakage between the button and the flange 5. The plunger has a 55 filler opening 16 and the passage through

the tube 3 is normally closed by means of the ball valve 17. When the plunger is in its lowermost position, the projections 18 formed from the metal of the plunger prevent the ball from jumping too high from its seat.

When the lubricator is to be filled, the plunger 8 is lifted until the rib or spline 7 is above the flange 5 when the plunger is 60 turned, as in Fig. 1, the lower end of the rib 7 resting on the flange 5 which constitutes a circumferential shoulder. The lubricator may now be filled through the hole 16. The plunger is of sufficient length to still inclose 65 the ball 17 when the plunger is at its highest position and prevent it from rolling off the end of the part 3.

When the plunger is released and forced to the position shown in Fig. 2, the ball 17 is permitted to roll on the upper end of the tube 3 to open the passage therein, but because the interior diameter of the plunger 8 is little greater than the diameter of the ball, this movement will be very small. The ball 70 will almost instantly resume its position over the passage in the part 3. The amount of lubricant flowing from the lubricator through the tube 3 will be determined by this difference in diameters and also by the tremors and jars of the machinery upon which 75 this device is mounted.

Instead of forming the rib at the upper end of the plunger and the notch in the flange 5 at the top of the cap of the body, the 80 rib 19 may be formed near or below the middle of the plunger and the guide plate 9 may be formed with a notch 20 to receive the rib. In this case, the guide plate constitutes the circumferential shoulder upon which the 85 end of the rib rests when the plunger is in its elevated position to uncover the opening 16.

I claim:

1. The combination of hollow interior and exterior members, one of said members having an internal guide plate and the other an external flange, a spring between the guide plate and flange, one of the members having a longitudinal rib and the other 105 member a notch in which the rib is slidable and from which the rib may be moved to permit the ribbed member to be turned.

2. The combination of hollow exterior and interior members, the exterior member having an internal guide plate and the interior member having a circumferential flange, a 110

spring between said plate and flange, said interior member having a longitudinal rib and the exterior member being formed with a notch in which the rib is slideable and from 5 which the rib may be moved to permit the interior member to be turned.

3. In a lubricator, the combination of an outer stationary member provided with an inwardly extending rim and a guide plate, 10 an inner movable member provided with a filler opening, a longitudinal rib and a circumferential flange, and a coil spring between the plate and flange, said outer member having a guide notch to receive said rib and 15 out of which the rib is moved when the filler opening is exposed.

4. In a lubricator, the combination of an outer stationary member provided with an inwardly extending rim and a guide plate, 20 a hollow inner movable member provided with a filler opening, a longitudinal rib and a circumferential flange, and a coil spring between the plate and flange, said plate being formed with a guide notch to receive 25 said rib and out of which the rib is moved when the filler opening is exposed, said rib riding upon the plate when the inner member is turned.

5. In a lubricator, the combination of hollow 30 interior and exterior members, the interior member having a filler opening, means to move the interior member downwardly, a guide plate within the exterior member and provided with a notch, and a longitudinal rib on the interior member adapted to move in said notch.

6. In a lubricator, the combination of hollow 35 interior and exterior members, the interior member having a filler opening and the exterior member having a discharge opening, means to move the interior member downwardly to close the filler opening, a ball valve within the interior member to normally close the discharge opening in the 40 exterior member, said interior member having a longitudinal rib and the exterior mem-

ber having a guide plate provided with a notch to receive said rib.

7. In a lubricator, the combination of hollow 50 interior and exterior members, the interior member having a filler opening, means to move the interior member downwardly, said exterior member being provided with a notched guide for the interior member and said interior member having a longitudinal 55 rib adapted to slide within the notch in the guide and to rest upon the guide when moved out of it and after which the interior member is turned.

8. In a lubricator, the combination of hollow 60 interior and exterior members, the interior member having a filler opening, means to move the interior member downwardly, said exterior member being provided with a notched guide for the interior member and said interior member having a longitudinal 65 rib adapted to slide within the notch in the guide and to rest upon the guide when moved out of it and after which the interior member is turned, said exterior member being formed with a discharge opening, a ball valve normally closing said opening and limited in its lateral movements by the 70 interior member.

9. In a lubricator, the combination of hollow 75 interior and exterior members, the interior member having a filler opening, means to move the interior member downwardly, said exterior member being provided with a notched guide for the interior member and said interior member having a longitudinal 80 rib adapted to slide within the notch in the guide and to rest upon the guide when moved out of it and after which the interior member is turned, said exterior member being formed with a discharge opening, a ball valve normally closing said opening and limited in its lateral movements by the 85 interior member, said interior member having inwardly extending projections to limit the 90 upward movement of the ball.

JOSEPH HORVATH.
